UNITED STATES PATENT OFFICE.

HARVEY J. HENRY, OF MASSILLON, OHIO.

GAS-ENGINE.

No. 853,303.

Specification of Letters Patent.

Patented May 14, 1907.

Application filed March 9, 1907. Serial No. 361,470.

To all whom it may concern:

Be it known that I, HARVEY J. HENRY, a citizen of the United States, residing at Massillon, in the county of Stark and State of Ohio, have invented certain new and useful Improvements in Gas-Engines; and I do hereby declare that the following is a full, clear, and exact description of the same, reference being had to the annexed drawings, making a part of this specification, and to the numerals and figures of reference marked thereon, in which—

Figure 1 is a vertical section taken at right angles with the power shaft. Fig. 2 is a vertical section parallel with the power shaft.

The present invention has relation to gas engines, and it consists in the novel arrangement hereinafter described and particularly pointed out in the claims.

Similar numerals of reference indicate corresponding parts in all the figures of the drawings.

In the accompanying drawing, 1 represents the piston cylinder, which is of the usual construction, and is surrounded by the water jacket or casing 2. Within the piston cylinder 1 is slidably mounted the piston 3, to which is attached the pitman 4, which pitman is connected to the power shaft 5 in the usual manner. At one side of the piston cylinder 1 is located the intake chamber 6, to which is attached in the usual manner the supply pipe 7, said supply pipe being provided with the usual valve 8. It is well understood that the top or upper end of the piston cylinder 1 is to be supplied with the gas to be ignited at the time the piston 3 is forced downward and in order to provide for a sufficient amount of gas to enter the crank and compression chamber 9 the intake chamber 6 is provided at its lower or bottom end with the vertical opening or gas passage 10, and the horizontal passage 11, which horizontal passage is provided with the bridge 12, said bridge being for the purpose of preventing the piston rings from catching upon the upper and lower edges of the horizontal passage 11.

It will be understood that by providing the vertical passage 10 and the horizontal passages 11 the gas is free to enter the crank chamber 9 when the piston is moved upward; and by providing both horizontal and vertical passages the gas is shunted both downward and in a horizontal direction, thereby completely filling the crank and com-

pression chamber with gas and better equalizing the pressure, and after an explosion has taken place and upon a downward movement of the piston 3, the gas is forced out of the compression or crank chamber into the intake chamber through the horizontal and vertical passages 3 and into the intake chamber 6 and thence through the passage or port 13.

It will be understood that the valve 8 should be an ordinary check valve or inlet valve so that it will cut off the back pressure during the time the piston moves downward, by which arrangement the gas is compressed in the intake chamber and when the piston is moved downward to a point below the top of the intake port 13, the gas in the intake chamber is released and finds its way into the piston cylinder 1. For the purpose of preventing the new charge of gas from mingling with the burnt gas after an explosion, the deflecting plate 14 is provided, which deflecting plate is secured to the piston 3 in any convenient and well known manner.

It will be understood that the exhaust port 15 is to be provided and is of the usual construction. The spark plug 16 is of the usual construction, but within itself forms no particular part of the present invention.

It will be understood that the gas should be confined in the crank and compression chamber during the downward stroke of the piston except as released for a new charge through the passages 10 and 11 and the port 13, and in order to prevent any leakage the power shaft is provided with the rings 17, which rings are seated in the grooves 18 formed in the bearings or boxings 19.

It will of course be understood that the piston cylinder is to be water cooled in the usual manner by a circulation of water by means of the inlet pipe 20 and the outlet pipe 21. I have discovered by actual use that during the time the engine is running slowly it is difficult to supply a sufficient amount of gas, but by providing the large intake chamber 6 and the horizontal and vertical passages 10 and 11 this difficulty is entirely overcome, owing to the fact that the intake chamber can be instantly recharged the instant the piston starts on its downward movement as there is both horizontal and vertical passage into the intake chamber and the passages can be formed of such a size that the gas is free to pass from the compression chamber into the intake chamber and thence into the piston

cylinder. Another advantage consists in removing practically all of the gas from the compression chamber, when the piston has reached its lowermost points.

5 Having fully described my invention, what I claim as new and desire to secure by Letters Patent, is—

1. In a gas engine, a piston cylinder, a piston located therein, a pitman and a power shaft, an intake chamber located at one side of the piston cylinder, said intake chamber provided with vertical and horizontal passages, a port located in the upper portion of the intake chamber and a deflecting plate secured to the piston, and a crank and compression chamber, substantially as and for the purpose specified.

2. In a gas engine, the combination of a piston cylinder, a piston located therein, a crank chamber, a power shaft located through said crank chamber, said power shaft provided with rings and the rings seated in the boxings of the power shaft and an intake chamber provided with horizontal and vertical passages and a port located in the upper portion of said intake chamber, substantially as and for the purpose specified.

In testimony that I claim the above, I have hereunto subscribed my name in the presence of two witnesses.

HARVEY J. HENRY.
